UNITED STATES PATENT OFFICE.

HARRY A. FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

PLATEN EQUIPMENT FOR TYPE-WRITING MACHINES.

1,116,812.

Specification of Letters Patent. Patented Nov. 10, 1914.

Application filed February 6, 1911. Serial No. 806,928.

To all whom it may concern:

Be it known that I, HARRY A. FOOTHORAP, a citizen of the United States of America, residing at Harrisburg, in the county of 5 Dauphin and State of Pennsylvania, have invented certain new and useful Improvements in Platen Equipment for Type-Writing Machines, of which the following is a specification.

10 This invention relates to what are known as flat platen typewriters, and more particularly to the equipment of the platen with means facilitating the manipulation and use of certain forms and combinations of work 15 sheets or strips and transfer elements.

Considered more specifically, the object of the invention is to equip a platen with devices for facilitating transportation billing, which involves what is known as multi- 20 billing, by means of a manifold strip and also multi-billing by means of a series of separate sheets.

In order to aid in comprehending the subsequent description of the structure, it 25 may be well, by way of premise, to state that in transportation billing so-called, there is necessity for making three or more copies of each freight bill and a much larger number of manifest sheets, which 30 latter are in effect condensed records of the bills minus the headings and also include data not included in the bills. One copy of each bill is retained by the consignor, another copy is transmitted to and retained 35 by any connecting line which may handle the freight billed, and the third copy is designed for the consignee. The various copies of the manifest constitute records for the use of the carrier, terminal agents, etc., 40 and also constitute checking records for the various auditing officials of the transportation system. Multi-billing by means of a manifold strip whereby a plurality of connected copies of each bill may be secured 45 is not unknown; see Patent No. 773,287 issued to Hiram J. Halle, October 25, 1904.

The present invention is directed to the equipment of the platen with transfer elements laterally movable in different directions into opposite folds of the manifold strip and so mounted that the lengthwise feed of the strip will be unobstructed and that the strip and its transfer elements with-

out disturbance of their interrelation, may 55 be moved away from the writing surface of the platen to facilitate the displacement of the subjacent printed manifest sheets and their replacement by unused sheets, the manifold strip and its transfer means being 60 movable back to normal position for continuation of the billing operation without disturbing the longitudinal adjustment of the strip.

The invention is further directed to the 65 provision of additional transfer means designed to transfer the impression from the manifold strip to a subjacent manifest or other sheet and associated with the movable support of the manifold strip for displacement and replacement therewith when access to the subjacent sheet or sheets is desired for any purpose.

The invention is further directed to a 75 novel arrangement whereby the manifold strip and its transfer means are carried by a movable support which, in its normal position, constitutes a work holder which retains the subjacent sheets in proper position on the platen and which, when moved 80 from normal position, carries the manifold strip and the transfer means away from the subjacent sheets and simultaneously releases said sheets, to the end that the mere act of moving the strip support will simultaneously release the subjacent work sheets 85 and render the same accessible for displacement or adjustment.

Other aspects of the invention and subordinate objects thereof will hereinafter 90 more fully appear.

In the accompanying drawings Figure 1 is a perspective view of an Elliott-Fisher typewriter associated with a platen equipped in accordance with my invention. Fig. 2 is a 95 similar view showing the track frame raised, the machine being indicated in dotted lines. Fig. 3 is a detail perspective view of a portion of the manifold strip or web. Fig. 4 is a plan view of the platen with portions thereof broken away and omitting the work and transfer elements. Fig. 5 is a front end view of the platen partly broken away to enlarge the scale. Fig. 6 is a longitudinal sectional view of the platen partly broken 105 away. Fig. 7 is a transverse section of the same subject-matter. Fig. 8 is a perspective view of the platen showing the transfer

leaves swung apart. Fig. 9 is a perspective view of one of the transfer bars with the adjacent portion of the transfer web indicated in dotted lines, and Fig. 10 is a detail sectional view showing the mounting of one of the transfer bars.

1 indicates a stationary flat platen upon the opposite side margins of which are imposed tracks or guides 2 upon which 10 travels, longitudinally of the platen, the main machine frame 3 supporting a laterally movable carriage 4 upon which is mounted key-operated printing mechanism, as is well understood in the art. The rear 15 end sections 5 of the tracks or guides 2 are fixed to the platen and constitute a stationary machine support for the reception of the machine when the latter is moved back from the printing area of the platen, as indicated in Fig. 2. The front track sections 6 are hinged at their rear ends, as indicated at 7, and are connected at their front ends by a frame bar 8 to form a vertically swinging frame 9 ordinarily designated a track 20 frame and which in the present connection may be variously regarded as a work holder, a machine support, or a carrier for the manifold web and certain transfer elements, as will more fully appear.

30 Disposed parallel with one side edge of the platen and extended somewhat above the writing surface is a work gage or abutment strip 10 screwed or otherwise secured to studs 11 extending laterally from the side 35 edge of the platen. The gage 10 is designed to constitute an abutment for the left hand edges of a series of flat work sheets 12 supported by the platen and preferably alternating with interposed carbon or trans- 40 fer sheets. In the normal position of the frame 9 the side members or track sections 6 thereof overlie and retain the work sheets 12, which are further held in a flat, spread-out condition by transverse work-holding 45 or guarding webs 13 extending between the rails 6 and adjustable longitudinally of the latter.

The rear extremities of the rear track sections 5 are extended beyond the rear end of 50 the platen and are connected by a cross-bar 14 spaced from the platen, as shown in Figs. 4 and 6. Extended rearwardly from the bar 14 are two bearing brackets 15 which constitute side guides for a manifold strip or web 16 which passes over a guide roller 17 mounted in the brackets 15 from a suitable source of supply, as for instance from a box or other receptacle in which the unused web is folded. The manifold sheet or web 60 16 passes from the roller 17 over the cross-bar 14, thence over the platen and sheets 12 mounted thereon, and finally passes over and drops down in advance of the frame bar 8, see Fig. 6.

65 A portion of the web 16 is shown in Fig.

3 and will be seen to be formed by folding a long web of paper in opposite directions along longitudinal lines to produce a series of superposed plies or layers *a*, *b* and *c* connected by opposite longitudinal folds *d* and 70 *e*. The upper surface of each layer or ply of this strip is in the present instance provided with longitudinally extending series of freight bill blanks printed thereon, each bill including the usual heading, below which 75 are the lines dividing the bill into columns. A number of these bill blanks overlie the writing surface of the platen and are filled in successively by advancing the machine over the platen in the usual manner. When 80 the set of bills overlying the platen have been filled in, the strip is drawn forward until an unused set of bill blanks is opposite the writing surface to permit a repetition of the operation, it being obvious that if 85 transfer material is interposed between the layers of the web the transfer of the impression to the underlying layers will produce a given bill record in triplicate. Where, as in the present instance, a condensed record is sought simultaneously with the billing, a single bill is first made out 90 and then the strip is advanced independently of the subjacent sheets until the space for the first entry on the next bill is opposite the next unused space on the condensed record sheet, this manipulation of the bill strip after the writing of each bill being necessary to prevent the waste of space on the record sheet, which would otherwise be 95 coincident with the headings of the bills.

The provision of transfer means for the manifold strip 16 involves some difficulty, the length of the strip rendering the use of coincident longitudinal carbon webs impractical and the fact that the layers of the strip are connected along longitudinal edges precluding the use of transfer carbons extending between carriers at opposite sides of the strip. It has therefore been proposed to 105 mount swinging transfer elements or leaves at opposite sides of the strip and arranged to be swung laterally into the opposite folds of the strip and held stationary as the strip is fed forward. The use of such leaves is 110 contemplated by the present invention, but the construction and arrangement thereof is materially different from anything heretofore suggested. In Fig. 8 the two transfer leaves 18 and 19 are shown, extending 115 lengthwise of the platen in superposed relation and secured or swung from their outer edges to enable them to be swung into the opposite folds of a manifold strip and to lie in alternating relation to the plies or layers 120 thereof.

Each transfer leaf 18 comprises an inked or carbonized paper or fabric strip or ribbon 20 provided with terminal loops 21 which receive transversely disposed bars or 130

blades 22 preferably of flat metal each of which is hingedly mounted at its outer end. The character of this mounting is clearly shown in Figs. 8 to 10 and includes a tubular sleeve 23 formed by bending or curling the end of the blade to receive a hinge rod or pintle 24 passed through and supported by blocks 25 and 26 the opening in the latter being of sufficient size and threaded to receive an externally threaded bushing 27 having a knurled head 28 and bearing at its inner end against one end of the sleeve 23. The blade 22 swings freely from the pintle 24 to permit the transfer web to be swung into and out of the fold of the manifold strip. The bushings 27 while forming bushings or linings for the blocks 26 are primarily designed as tension devices for the transfer webs, since it will be seen that by rotating these bushings in the proper direction the two blades at the opposite ends of the web will be urged apart thus holding the intervening portion of the web perfectly taut and causing the latter to lie smooth and unwrinkled within the manifold strip. The bushings 27 therefore constitute means for adjusting the transfer blades 22 laterally and may also be regarded as tension mechanism for the transfer webs. The rear bearing blocks 25 for the blades 22 located at the rear end of the platen are screwed or otherwise secured to the cross-bar 14 while the adjacent blocks 26 are similarly secured to the upper surface of the platen, as shown in Figs. 6 and 8. It will thus be seen that the mountings for the two rear blades 22 are carried by stationary portions of the platen structure. The front blades 22, on the contrary, are mounted on the frame 9 for which purpose the blocks 25 are mounted on the frame bar 8 while the adjacent blocks 26 are mounted on a second frame bar 30 secured to the under sides of the movable track sections 6 in rear of the bar 8, but somewhat in advance of the front end of the platen, see Figs. 6 and 8. In order to prevent the displacement of the transfer webs 20 from the blades 22, the outer side edges of the latter may be and preferably are formed with spurs 31 preferably formed integral with the blades, see Fig. 9. When the loops of the web 20 are slipped over the blades the spurs 31 will pass through and secure the webbing.

It will now be seen that in accordance with my invention the platen equipment includes transfer webs extending longitudinally of the platen and terminally secured to swinging blades which coact with the webs to form hinged transfer leaves mounted beyond opposite sides of the manifold strip and adapted to be swung in opposite directions into opposite folds of said strip and to lie one above another opposite the same area of the platen. It will also be noted

that that portion of the transfer leaves lying between the terminal blades is flexible and that while the rear ends of the leaves are mounted on a fixed part of the platen structure, the front ends of said leaves are carried by the frame 9 which, as we have seen, is movable toward and away from the platen for the purpose of releasing and rendering accessible the work sheets 12 disposed upon the platen below the manifold strip. This construction and arrangement of the leaves 18 and 19 permits their front portions to be raised with the frame 9, as shown in Fig. 2, while their rear ends lie undisturbed in normal position within that portion of the manifold strip located over the machine support in rear of the rail hinges 7. In other words, the arrangement is such that the manifold strip and the interposed transfer leaves may be raised away from the platen with the frame 9 without in any way disturbing the relation between the strip and the transfer medium. The maintenance of this proper relation is also aided by the work-holding guide bars or webs 13 which serve not only to aid in the holding and guarding of the subjacent work sheets, but also support that portion of the manifold web which extends over the writing surface and prevent the web from dropping materially when the frame 9 is raised. In order to allow the blades 22 to normally lie in somewhat lower planes than the hinges, the hinged ends of the blades are bent, as indicated at 31', into angular relation to the body portions of the blades.

In addition to the transfer leaves for the manifold strip, it is desirable to equip the platen with additional transfer means which in the present instance is in the form of a web or ribbon 32 extended longitudinally over the platen below the manifold strip and above the uppermost manifest sheet, so that, as a bill is made out in triplicate on the manifold strip the printed data will be transferred by the web 32 to the uppermost manifest sheet and thus to the subjacent manifest sheets through the medium of the interposed carbons. The transfer web 32 has its opposite end wound upon spindles or carriers 33 and 34 provided with knurled heads 35 by means of which the spindles may be rotated to feed the web 32 from one to the other. The rear spindle 33 is preferably mounted in the brackets 15 below the cross-bar 14, while the front spindle 34 is mounted in bearing blocks 36 secured to the under side of the frame bar 8 by bolts or screws 37 which constitute retaining means common to the blocks 36 and the adjacent block 25. It will thus be seen that the transfer web 32, like the webs 20 of the leaves 18 and 19, is retained at its rear end by a carrier located in rear of the track frame and at its front end is secured to

the track frame to insure its elevation by the latter when access to the manifest sheets is desired. The web 32 may be passed over or under the work-holding members 13 and 5 the bar 30. In any event, when the work frame is thrown up to the position indicated in Fig. 2, the manifold strip 16, the front portions of the transfer leaves 18 and 19 and the front portion of the transfer web 32 10 will all be carried with it away from the subjacent work sheets and will all be carried back to normal position by the mere act of lowering the frame to clamp the sheets on the platen.

15 Briefly, the operation of the described mechanism is as follows: Assuming the parts to be in normal position, the machine is moved forward on the platen, for instance to the position shown in Fig. 1, and the 20 operator proceeds to make out a bill on the uppermost layer of the manifold strip 16. The matter thus printed is transferred to the two lower layers of the strip to produce the bill in triplicate. The data thus printed 25 on the bill is transferred to the uppermost manifest sheet 12 by the transfer web 32 and, to subjacent manifest sheets by interposed carbons. It will be noted that the manifold or bill strip extends over approximately one-half only of the platen so that a 30 considerable portion of the sheets 12 extend beyond the right hand edge of the manifold strip. This is for the reason that the manifest sheets are designed to receive data, 35 which is not desired shall appear in the bill, but which applies to the latter and must therefore be printed on the manifest sheets opposite the transferred copy of the bill. Therefore, having made out a bill, the operator 40 shifts the carriage of the machine from its position over the bill strip to a position opposite the exposed portion of the upper manifest and she enters upon the latter the required data, which is transferred to the subjacent manifest sheets by the carbons. 45 Preparatory to making out the next bill, the operator grasps the front end of the manifold strip and draws the same forward until the first writing line of the next bill 50 blank in rear of the one written is brought to a position one line in advance of the last entry on the exposed portion of the manifest sheet. She then imparts one line space movement to the machine and proceeds to 55 make out the next bill; the record of which will be transferred to the manifest sheets immediately below the preceding bill and thus produce a condensed record of the bills on the manifest. When the manifest sheets 60 have been filled, the carriage is moved back to the rear end of the platen, the frame 9 is elevated, as shown in Fig. 2 to release the sheets 12 and to render the same readily accessible by removing therefrom the manifold strip, its transfer elements and the

transfer web 32. The manifest sheets 12 are then removed, a new set of such sheets are placed upon the platen with their left hand edges against the gage or abutment 10, the frame 9 is dropped to clamp said sheets and to restore the strip 16 to normal position, and the billing operation as before described is continued. 70

It is thought that from the foregoing, the construction, operation and advantages of this platen equipment will be fully comprehended, but while the illustrated embodiment of the invention appears at this time to be preferable, I expressly reserve the right to effect such changes, modifications 75 and variations of the construction and arrangement shown as may come fairly within the scope of the protection prayed. 80

What I claim is:—

1. The combination with a platen and a 85 support for a work element, said platen and support having relative separative movement to separate the work element and platen, a transfer element, and means for mounting the transfer element to permit movement thereof into and out of co-operative relation with the work element, said transfer element being separated from the platen by the relative separative movement of the platen and support. 90

2. The combination with a platen, of a transfer element, a mounting therefor arranged to swing about an axis to move said transfer element into and out of co-operative relation with the work sheet, said 100 mounting having a different movement toward and from the platen to effect a separative movement of the platen and transfer element.

3. The combination with a stationary 105 platen and a printing mechanism mounted to travel over the platen, of a normally stationary transfer element, a carrier therefor, said carrier being movable relative to the stationary platen to present the transfer element opposite the printing area of the platen and said carrier also having a different movement to carry the transfer element away from the platen while retaining the same opposite the printing area. 110

4. The combination with a flat platen, of means for holding a work element opposite the platen, said holder and platen having relative separative movement, a transfer element, a carrier for said transfer element 120 arranged to swing the transfer element into and out of normal position with reference to the work element, said transfer element and platen being separated by the relative separative movement of the work holder 125 and platen.

5. The combination with a platen, of a transfer element, and a carrier therefor movable to shift said transfer element laterally into and out of a position oppo- 130

site a given printing area of the platen and also movable to shift the transfer element toward and away from the platen with the work element while opposite said printing area.

6. The combination with a platen and a support having relative separative movement, of a transfer element movable on said support in a direction which is lateral with respect to the transfer element and longitudinal with respect to the lines of writing.

7. The combination with a platen, of a support movable relative to the platen in a direction substantially perpendicular to the writing surface, and a transfer element carried by the support and laterally movable independently thereof toward and from a given printing area of the platen.

8. The combination with a platen and a support having relative separative movement, of a transfer element mounted on the support to participate in such relative separative movement and also arranged to swing on said support.

9. The combination with a platen and a support having relative separative movement, of a transfer element carried by the support and movable independently of the support in a direction which is lateral with respect to said element.

10. The combination with a platen, of a swinging support and a transfer element mounted to swing with the support and also to swing relative to said support, the two axes of movement of said element being angularly related.

11. The combination with a platen, of a support mounted to swing toward and away from the writing surface of the platen, a transfer element carried by the support and mounted to swing relative thereto, to displace the transfer element from the printing area, the axes of the support and transfer element being angularly related.

12. The combination with a platen, of a swinging supporting element and a swinging transfer element carried by the supporting element, the axis of one of said elements being substantially parallel with the line of writing and the axis of the other element being disposed at an angle to said line.

13. The combination with a platen, of a support having a separative movement toward and away from the writing surface thereof and a transfer element movable toward and away from the platen with said support and also movable toward and away from the support.

14. The combination with a platen, of a support having a separative movement toward and away from the platen, of a transfer element and a transfer carrier movable with the support and also movable relative

to the support to shift the transfer element toward and away from a position opposite a given printing area of the platen.

15. The combination with a flat platen, of a support having a separative movement toward and away from the writing surface thereof, and a transfer element carried by the support and movable independently thereof toward and from the platen.

16. The combination with a platen, of a work holder co-operating therewith and a transfer element mounted on the work holder and movable relative thereto to shift the transfer element laterally toward and from a given area of the platen.

17. The combination with a platen, of a work carrier movable to carry a work element toward and away from the platen, and a transfer carrier movable with the work carrier to retain a transfer element opposite the work element, said transfer carrier being movable relative to the work carrier to shift said transfer element laterally toward and away from the work element.

18. The combination with a platen and a work carrier relatively movable, of a transfer carrier associated with the work carrier and movable relative thereto to shift the transfer element laterally.

19. The combination with a platen, of a swinging work carrier and a transfer element mounted to swing on the work carrier.

20. The combination with a platen, of a hinged frame coacting with the platen to retain a work sheet in the printing position, of a transfer carrier hinged to the frame.

21. The combination with a platen, of a transfer element and spaced transfer carriers or holders retaining said transfer element opposite a given printing area and movable to shift the same laterally away from said area and one of said carriers being movable independently of the other to move the adjacent portion of the transfer element toward and away from the platen.

22. The combination with a platen, of a flexible transfer element and spaced transfer carriers, said carriers being movable in unison to withdraw the transfer element from a given printing area of the platen and one of said carriers being movable independently of the other to move the adjacent portion of the transfer element away from the writing surface of the platen.

23. The combination with a platen, of a flexible transfer element and spaced hinged transfer carriers, one of said carriers being movable independently of its hinge movement.

24. The combination with a platen, of a work holder connected thereto to move toward and from the platen, and a swinging transfer carrier mounted on said holder.

25. The combination with a flat platen, a movable printing machine and a movable

- machine support, of a transfer element movable with the support and also movable relative to said support, toward and from a given printing area of the platen.
26. The combination with a flat platen, of a swinging work holder coöperating therewith, and a flexible transfer element, one end of said transfer element being carried by the swinging work holder and the other end of said transfer element being mounted independently of said holder whereby when the work holder is elevated that portion of the transfer element extended over the printing area of the platen will be removed therefrom.
27. The combination with a platen, of a plurality of transfer elements movable laterally in opposite directions to dispose the same in opposite folds of a manifold sheet or strip, and means for moving said transfer elements toward and away from the platen to permit access to such work elements as may underlie the manifold sheet or strip.
28. The combination with a platen, of a plurality of transfer elements mounted to swing laterally in opposite directions to dispose the same within opposite folds of a manifold sheet strip and also having a different movement toward and from the platen to permit access to an underlying work sheet.
29. The combination with a platen, of front and rear hinged carriers, a plurality of transfer elements extended between said carriers and mounted to swing in different directions to dispose said transfer elements within opposite folds of a manifold sheet or strip, and means for moving the front carriers toward and from the platen independently of the individual swinging movements of said carriers.
30. The combination with a platen, of a swinging frame having supporting and guiding means for a manifold sheet or strip, a plurality of transfer elements, and carriers for said transfer elements mounted on the frame.
31. The combination with a platen and a typewriting machine having the usual ink ribbon, of a plurality of oppositely hinged transfer elements disposed over the platen, an additional transfer element, and rotary carriers therefor.
32. The combination with a platen, of a series of transfer elements, and means for mounting said transfer elements, said means permitting lateral and longitudinal movement of different transfer elements.
33. The combination with a platen, of an abutment facilitating the positioning of the work sheets, a work holding frame coöperating with the platen to hold the sheets positioned by the abutment, and a plurality of laterally movable transfer elements sup-
- ported by the frame and arranged to be positioned within opposite folds of a manifold sheet or strip.
34. The combination with a flat platen, of vertically movable confining means for a work sheet, a transfer element movable toward and from the platen with said confining means and also movable laterally independently of the confining means.
35. The combination with a flat platen, of a transfer element disposed longitudinally thereof and movable transversely of the platen into and out of operative position, and means for moving the transfer element toward and from the platen to facilitate access to subjacent work elements.
36. The combination with a platen, of a transfer carrier mounted to swing in one direction, and means for shifting the transfer carrier in a different direction and for holding it in its shifted position.
37. The combination with a transfer strip, a carrier retaining one end of the strip, an axial support for said carrier, and means associated with said axial support for shifting said carrier.
38. The combination with a platen and a printing mechanism including the usual ink ribbon of a plurality of oppositely swinging transfer carriers, and an adjacent rotary transfer carrier.
39. The combination with a flat platen, of a plurality of oppositely swinging transfer carriers and a rotary transfer carrier disposed adjacent to each of two opposite edges of the platen, transfer elements extended between the swinging transfer carriers, and a transfer element extended between the rotary transfer carriers.
40. The combination with a platen, of a support movable toward and from the plane of the platen, a laterally movable transfer element carried by the support, and a longitudinally movable transfer element also carried by said support.
41. The combination with a work confining frame, of a transfer element movable transversely of the platen on the frame, a second transfer element, and means carried by the frame for moving one of said transfer elements longitudinally.
42. The combination with a flat platen and a movable support, of a plurality of transfer elements extended longitudinally of the platen and having their front ends carried by the support, and means for feeding one of said elements longitudinally independently of another transfer element.
43. The combination with a flat platen, of two transfer carriers mounted to swing about axes disposed longitudinally of the platen, a transfer element extended between said carriers, and a movable support for one of said carriers.
44. The combination with a platen and

a work-holder having relative separative movement, of a transfer element, and a transfer carrier carried by the work-holder and movable relative thereto to shift the transfer element.

45. The combination with a platen and a work-holder having relative separative movement, of a transfer element, and a transfer carrier carried by the work-holder and

movable relative thereto to shift the transfer element laterally.

In testimony whereof I affix my signature in presence of two witnesses.

HARRY A. FOOTHORAP.
